UNITED STATES PATENT OFFICE.

THAD CLARK, OF AMERICUS, GEORGIA.

PEN.

Application filed September 20, 1921. Serial No. 501,896.

To all whom it may concern:

Be it known that I, THAD CLARK, a citizen of the United States, residing at Americus, in the county of Sumter and State of Georgia, have invented new and useful Improvements in Pens, of which the following is a specification.

This invention relates to improvements in fountain pens and has for an object the provision of a "self filling" fountain pen having automatically operated means for closing the filling opening, whereby, when the pen is held in a vertical position for filling, the opening will be automatically closed, but will be automatically opened when the pen is held in writing position.

Another object of the invention is the provision of novel means for filling the pen, whereby the above mentioned closing means will be opened to permit of the entrance of ink into the pen, means being provided for cutting off the ink when the pen has become filled and for permitting of the escape of air as the parts are returned to their normal position.

With the above and other objects in view, the invention further includes the following novel features and details of construction, to be hereinafter more fully described, illustrated in the accompanying drawings and pointed out in the appended claims.

In the drawings:—

Figure 1 is a longitudinal sectional view through a fountain pen constructed in accordance with the invention and shown in writing position.

Figure 2 is a similar view of the pen in filling position, the parts being in the position occupied just prior to their return to normal position.

Referring in detail to the drawings, wherein like characters of reference denote corresponding parts, the reference character 10 indicates the body of the pen which is of hollow tubular formation and is threaded at its lower end to receive a plug 11 which carries a pen point 12. This pen point is held in place by a grooved bar or wedge 13, so that ink from the interior of the pen body will be fed to the point by capillary attraction, in the usual well known manner.

The opening in the plug 11 which receives the point 12 and wedge 13 provides both an outlet for the ink when the pen is in use and an inlet port 14 to provide for

filling the pen. This port is closed by a ball valve 15 and the inner end of the plug 11 is concaved so that the ball will close the port 14 when the pen is held in a vertical position as shown in Figure 2 of the drawings, but will maintain the port in an open position when the pen is in use, as shown in Figure 1 of the drawings.

Operating within the body 10 is a tubular piston 16 which is provided at its inner end with a port 17. The inner end of the piston 16 is surrounded by spaced annular flanges 18 and 19, between which is positioned a washer 20. This washer bears against the inner wall of the body 10 so as to provide a leak proof joint.

The opposite end of the piston 16 has threadedly secured therein a plug 21 which is provided with a central bore 22. This bore is in communication with a relatively large bore or chamber 23, which together with the restricted portion of the bore provides an air exhaust port. The latter is normally closed by a spring actuated valve 24 which includes a head 24, the stem 25 and an operating head 26, the latter operating within the enlarged portion 23 of the bore, within which is also seated a spring 27. Surrounding the restricted portion 22 of the bore is a valve seat 28 which is adapted to be closed by a float valve 29 located within the piston 16.

The plug 21 also has a threaded connection with the body 10 as shown at 30, while a cap 31 threadedly engages said plug and closes the head 26 of the valve 24. If desired, the pen may be provided with a cap or cover 32 which may be threadedly secured to the plug 11 or frictionally secured upon the body 10, as shown in Figure 1.

In the use of the pen, when the latter is held in writing position, the ball 15 will be moved by gravity to one side of the center of the pen away from the port 14 so as to permit of a flow of ink to the pen point 12.

When it is desired to fill the pen, the point is placed within the ink, the cap 31 having previously been removed and the plug 21 disconnected from the body 10. The plug 21 is then pulled outward, the suction created thereby unseating the valve 15 and drawing the ink upward into the pen body. This outward movement of the piston 16 is continued until the annular flange 19 engages a flange provided at the outer end of the body 10. The float 29 will then

be positioned over the port 17, but an inward movement of the piston will unseat this float to permit ink to flow into the piston. To facilitate this, the head 26 is manually pushed inward to unseat the valve 24 so as to permit of the escape of air, so that the parts may be returned to their normal position. The plug 21 may then be re-engaged with the body 10 and the cap 31 replaced.

10 The invention is susceptible of various changes in its form, proportions and minor details of construction and the right is herein reserved to make such changes as properly fall within the scope of the appended claims.

15 Having described the invention what is claimed is:—

1. A fountain pen comprising a tubular body, a plug secured in one end thereof, a pen point carried by the plug, a port in said plug, a hollow tubular piston movable within the tubular body, a port at each end thereof, manually operated means for closing the port at one end of the piston, auto-

20 matically operated means for closing the port at the opposite end of said piston and means for automatically closing the port in the tubular body when the pen is in a vertical position and automatically opening said port when the pen is in an inclined position.

2. A fountain pen comprising a tubular body, a plug secured in one end thereof, a pen point carried by the plug, a port in said plug, a hollow tubular piston movable within the tubular body, a port at the inner end of the piston, means whereby the piston may be pulled outward to fill said body, a manually controlled air escape port located in the opposite end of the piston, a float valve controlling the port at the inner end of the piston and means for automatically closing the port in the tubular body when the pen is in a vertical position and automatically opening said port when the pen is in an inclined position.

25 In testimony whereof I affix my signature.

THAD CLARK.
